THERMIONIC VALVE CIRCUITS

Graham, John Scoles, East Sheen, London, England, assignor to Metropolitan-Vickers Electrical Company Limited, London, England, a company of Great Britain

Application September 21, 1943, Serial No. 503,280
In Great Britain August 8, 1941

2 Claims. (Cl. 250—27)

This invention relates to thermionic valve circuits and specifically to so-called limiter circuits. The invention is notably but not exclusively applicable in circuits wherein from complex or other received signals at least two different outputs are derived by means of a detector device or devices. The invention is applicable in the main to so-called "panoramic" radio receivers the nature of which was described in "Electronics," June, 1940, and wherein in brief a waveband, 10 or, it may be, any selected one of a plurality of wavebands, is scanned from end to end by the automatic variation of a tuning parameter at a rate comparable with the frequency of the persistence of vision; the output or outputs due to any received radio transmissions which may be taking place within the waveband being indicated as resonance or peak components perpendicular to a time base waveband component on the screen of a cathode ray tube, the time base component being provided synchronously with the scanning such as by means of a saw-tooth type of oscillation generator. Provision can be made whereby any selected one of the thus indicated transmissions can be tuned in manually and its modulation listened to or recorded or otherwise indicated, that is to say, the scanning of the waveband can be effected solely by hand such as through the turning of a knob about an associated dial indicating the wavelength. In such a panoramic receiver it has been convenient for the purpose of the rapid scanning of the waveband to "wobble" the value of certain tuning components of the oscillator section of a frequency changer valve in a superheterodyne circuit, which superheterodyne circuit preferably has three stages of frequency changing with corresponding intermediate frequency circuits, and preferably the scanning is effected by a reactor valve associated with the second oscillator through an amplifier as described in copending U. S. application of myself and John M. Dodds, Ser. No. 503,277, filed of even date herewith.

The present invention, according to one aspect thereof, provides a detector arrangement whereby one of the several outputs therefrom, such as the video output, is limited to approximately a predetermined value without, however, another output or other outputs, such as an audio output, being limited.

A known limiter arrangement (see British Specification No. 474,356) comprises a diode rectifier followed by a diode limiter such as for the video output from the detector diode, to the anode of which the signals, after suitable ampli-

fication, are applied, whilst the cathode of this diode is connected to the "earthy" busbar of the signal input circuit through two resistances in series (which may be collectively bridged by a smoothing condenser) the junction of said two resistances being connected to the anode of the limiter diode and through a condenser to said busbar, the cathode of the limiter diode being maintained at an appropriate positive potential conveniently by being connected to the junction point of two further resistances connected between a source of positive potential and said busbar. Of these resistances, the one connected between the cathode and busbar of the limiter diode may be variable. The anode of the limiter diode is connected also to the video amplifier or other utilisation circuit. The output from the detector diode may also be taken from a tapping (which may be variable) on that of the first-mentioned two resistances which is connected to the aforesaid busbar, and applied, for example, to an audio frequency amplifier.

With the known arrangement just above described, if the potential across the detector resistance between the limiter diode anode and busbar becomes greater than that across the resistance connected between the busbar and the cathode of the limiter diode, then the latter valve conducts and prevents further increase of output, but for satisfactory operation this largely depends upon the inherent poor regulation of the diode detector circuit.

The present invention comprises a thermionic valve circuit for detecting complex signals, wherefrom the different outputs are respectively extracted by a detector arrangement adapted to limit at least one of said outputs to approximately a predetermined value without limiting another output or outputs, the detector valve being arranged as a per se well known "cathode follower" or "infinite impedance" type, and having its cathode connected through a high resistance to the anode of a limiter diode, the cathode of which is positively biased. Said resistance must be high compared with the impedance of the diode.

The type of detector used in the present invention gives good regulation so that its output voltage is largely independent of the cathode load and so arranged that good response is obtained up to the higher frequencies which it is desired that the circuit shall deal with. Since the feed resistance from the detector cathode to the limiter diode anode is high compared with the im-

pedance of this valve, the output voltage from the limiter is limited to that of the cathode thereof, while the limiter circuit as a whole has no effect upon the output, such as audio output, which may be taken direct from the detector, in the known manner above described, and such is partly due to the relative impedances of the two circuits and partly due to the inherent good regulation of the cathode follower circuit.

It will be appreciated that there may be provided more than one limiter circuit.

The single figure of the accompanying drawing is a circuit diagram illustrating the invention, and it will be seen that the detector valve V_1 is of the cathode follower type having its cathode connected to the "earthy" busbar B through the resistance R in series with the potentiometer resistance R_1 across which latter is the condenser C_1 , whilst a condenser C_2 is connected across both resistances, the radio frequency input to the valve V_1 being applied between the control grid A and the busbar B . The cathode of the valve V_1 is connected through the high resistance R_2 to the anode of the diode V_2 and to the video stage such as indicated at $Vid. A$ in Fig. 1 of the drawings of my copending U. S. application Ser. No. 503,278, filed of even date herewith, whilst the tapping on the potentiometer R_1 is taken to the audio amplifier stage. The cathode of the diode V_2 is positively biased by the connection between resistances R_3 and R_4 connected between the positive supply and busbar B .

I claim:

1. In a thermionic valve circuit for detecting complex signals, means for extracting the different signal outputs respectively at different

terminals and for limiting at least one of said outputs to approximately a predetermined value without limiting audio output, comprising a detector valve having a cathode and a signal receiving grid and arranged as a cathode follower, a limiter diode having an anode and a cathode, means including a resistance connecting the cathode of the detector valve to the anode of the limiter diode, said resistance being high relatively to the impedance of the limiter diode, and the cathode of the limiter diode being positively biased, means for taking the limited signal output from the anode of the limiter diode, a resistance in the cathode circuit of the detector valve, and means for taking another signal output from said last named resistance.

2. A thermionic valve circuit for detecting complex signals, comprising a detector valve having a radio frequency input grid connected to one terminal of the circuit and a cathode coupled by a resistance to the other terminal of the circuit, a limiter diode having an anode and a cathode, means including a resistance connecting the cathode of the detector valve to the anode of the limiter diode, said resistance being high relatively to the impedance of said diode, the anode of said diode providing the output for a signal to be limited in value, series-connected resistances between one terminal of said circuit and a source of positive potential, a connection between the junction of said series-connected resistances and the cathode of the limiter diode, and means for taking a signal output from said first-mentioned resistance.

GRAHAM JOHN SCOLES.
